SKI CLAMP

Rune Joon, Gardesvagen 40, 793 00 Leksand, Sweden

Filed Sept. 27, 1974, Ser. No. 510,132

Claims priority, application Sweden June 27, 1974

Term of patent 14 years

Int. Cl. D8—08

U.S. Cl. D8—246

FIG. 1 is a perspective view of a ski clamp according to my new design;

FIG. 2 is a front elevational view thereof;

FIG. 3 is a top plan view thereof;

FIG. 4 is an end elevational view thereof.

I claim:

The ornamental design for a ski clamp, as shown and described.
